(57) **CLAIM**

I claim the ornamental design for a steam iron, as shown and described.

DESCRIPTION

FIG. 1 is a perspective view of a steam iron;

FIG. 2 is a front view of the steam iron;

FIG. 3 is a rear view of the steam iron;

FIG. 4 is a left side view of the steam iron;

FIG. 5 is a right side view of the steam iron;

FIG. 6 is a top plan view of the steam iron;

FIG. 7 is a bottom plan view of the steam iron;

FIG. 8 is a first reference view of the steam iron in use; and,

FIG. 9 is a second reference view of the steam iron in use.

The details shown in broken lines in FIGS. 8 and 9 form no part of the claimed design. The hose is shown broken away in FIGS. 8 and 9 for ease of illustration and is fully represented in the other views.
